(57) **CLAIM**

The ornamental design for a maglev speaker, as shown and described.

DESCRIPTION

FIG. 1 is a top perspective view of a maglev speaker showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof;

FIG. 7 is a top plan view thereof;

FIG. 8 is a top perspective view thereof, shown in use with a base; and,

FIG. 9 is a top perspective view thereof, shown in use with another base.

The broken lines in FIGS. 2-6 depict the portions of the maglev speaker that form no part of the claimed design. The broken lines showing bases in FIG. 8 and FIG. 9 depict environmental subject matter that forms no part of the claimed design.

1 Claim, 9 Drawing Sheets
